CARTON FOR STACKED ARTICLES

Guelfo A. Manizza, Blauvelt, N.Y., assignor to Continental Can Company, Inc., New York, N.Y., a corporation of New York

Filed May 18, 1966, Ser. No. 551,061
17 Claims. (Cl. 206—47)

ABSTRACT OF THE DISCLOSURE

This invention relates to a novel carton for stacked articles, and is particularly directed to a carton which embraces and partially houses two articles, such as containers, of two different sizes. The carton includes a body defining a chamber at least one end of which is closed. A flange portion of the lowermost container is received in an opening of the body defined by a flap thereof directed radially into the chamber, and an uppermost of the containers is housed in the chamber with its bottom surface at least partially overlyingly contacting the flap and being cushioned thereby.

A primary object of this invention is to provide a novel carton for maintaining a plurality of articles in stacked relationship including a generally tubular body having axially opposite end portions, the tubular body defining a chamber for wholly housing an uppermost article and partially housing a lowermost article, means for closing an uppermost one of the end portions, an opposite one of the end portions being devoid of closing means, and means for interlockingly engaging the tubular body with a lowermost of the articles.

A further object of this invention is to provide a novel carton of the type just described including means integrally formed from the material of the tubular body and projecting into the chamber for preventing complete contact between a bottom surface of the uppermost article and a top surface of the lowermost article whereby frangible articles are cushioned against breakage during storage and/or shipment.

A further object of this invention is to provide a novel carton of the type heretofore described wherein the opposite end portion of the tubular body is of an undulating configuration for matingly embracing an exterior surface of the lowermost one of the articles.

Another object of this invention is to provide a novel carton of the type heretofore described wherein the tubular body is defined by front, rear and side panels, and the interlocking means is an opening formed in each of the body panels into which is received a portion of the lowermost of the articles.

With the above and other objects in view that will hereinafter appear, the nature of the invention will be more clearly understood by reference to the following detailed description, the appended claims and the several views illustrated in the accompanying drawings.

In the drawings:

FIGURE 1 is a top perspective view of a novel carton constructed in accordance with this invention, and illustrates a lowermost article interlockingly secured to the carton and an uppermost article completely housed within a chamber thereof.

FIGURE 2 is a bottom perspective view of the carton of FIGURE 1, and illustrates radially inwardly directed flaps defining cushioning means between the uppermost and lowermost articles.

FIGURE 3 is an enlarged sectional view taken generally along line 3—3 of FIGURE 1, and illustrates an opening defined by flap portions of adjacent panels of the

2

carton through which the uppermost article can be viewed.

FIGURE 4 is an enlarged fragmentary sectional view taken generally along line 4—4 of FIGURE 1 with the articles shown in side elevation, and illustrates the manner in which the uppermost article is supported by the lowermost article and the interlocking securement of the lowermost article to the carton.

FIGURE 5 is a top plan view of a blank from which the carton of FIGURES 1 through 4 is constructed, and illustrates the generally planar configuration thereof prior to being formed into the carton and united with the articles.

A novel carton constructed in accordance with this invention is fully illustrated in FIGURES 1 through 4 of the drawings, and is generally designated by the reference numeral 10. The carton 10 is preferably constructed from a blank 15 (FIGURE 5) of generally planar sheet material such as paperstock or similar relatively foldable flexible material.

Referring first to the blank 15 of FIGURE 5 of the drawings, the blank 15 includes a generally planar sheet material member 16 defined by generally parallel transverse edges 17, 18 and longitudinal edges 20, 21. The longitudinal edge 21 is of a generally irregular configuration and defines a plurality of closure flaps 22 through 24, the latter including a closure tab 25.

The blank 15 is separated into a plurality of panels 26 through 30 by respective transverse fold lines 31 through 34.

The panel 26 is relatively narrow and is coated with conventional adhesive A, as is indicated by the stippling in FIGURE 5 of the drawings. The panel 26 is adapted to be secured to the panel 30 adjacent the transverse edge 18 to impart a generally tubular configuration to the blank 15, as will be more apparent hereafter.

For purposes of description the panel 27 is considered a rear panel, and is defined by the fold lines 31, 32, a portion (unnumbered) of the longitudinal edge 21, and an edge portion 35 opening concavely downwardly as viewed in FIGURE 5 of the drawings. A tab 36 is formed from the material of the panel 27 by means of a relatively shallow U-shaped cut or severance line 37. The tab or flap 36 is adapted to be folded radially inwardly along a fold line 38 during the setting-up of the blank 15, as will be more apparent hereafter.

The panel 28, which may be considered a first side panel, is defined by the fold lines 32, 33, a fold line 40 and another concavely opening edge portion 41 of the longitudinal edge 20. The side panel 28 similarly includes a tab or flap 42 defined by a generally U-shaped cut line 43 which is foldable along a fold line 44. The fold line 44 is in alignment with the fold line 38 and the tab or flap 42 is thereby adapted to be folded into a plane substantially coincidental to the plane of the flap 36. The fold line 33 is interrupted by a cut line 45 which is generally parallel to a fold line 46 adjacent the fold line 32. Severance lines 48, 50 join the cut line 45 and the fold line 46 and define therewith a flap or tab 51.

The panel 29 which may be considered to be a front panel is defined by the fold line 33, 34, a fold line 52 and a concavely opening edge portion 53 of the longitudinal edge 20. A generally shallow U-shaped severance line 54 defines a flap or tab 55 which is joined to the panel 29 along a fold line 56 which is parallel to the fold lines 38, 44 of the respective panels 27, 28. The panel 29 is similarly provided with a fold line 57 which is joined to the severance or cut line 45 by spaced cut lines 58, 59. The cut lines 45, 58 and 59, and the fold line 57 define a flap or tab 60 which is similar in configuration to the flap 51.

The panel 30, which may be considered a second side panel, is defined by the fold line 34, the transverse edge 18, a fold line 62 and a concavely opening edge portion 63 of the longitudinal edge 20. A generally shallow U-shaped severance line 64 defines a tab or flap 65 which is joined to the panel 30 along a fold line 66. The fold line 66 is similarly coincident to the fold lines 38, 44 and 56.

A pair of articles A1, A2 are secured together in stacked relationship by the carton 10 in the manner best illustrated in FIGURES 1 and 4 of the drawings by the folding of the blank 15 to a generally tubular configuration. The articles A1, A2 are preferably jars or containers J1, J2 which include respective reduced threaded necks N1, N2 which are closed by respective closures C1, C2. The container or jar J2 is relatively larger in axial length and diameter, as compared to the axial length and diameter of the container J1.

The jar J2 is first filled with a suitable edible or non-edible product which may be, for example, coffee, after which the closure C2 is secured to the threaded neck N2. The flaps or tabs 36, 42, 55 and 64 are then folded in the same direction generally normal to the respective panels 27, 28, 29 and 30 of the blank 15 and the blank 15 is wrapped about the neck N2 in a manner which permits arcuate portions of the closure C2 to project through the openings (unnumbered) defined by the now folded tabs 36, 42, 55 and 65. The tabs 36, 42, 54 and 65 are positioned above the uppermost surface of the closure C2, as is best illustrated in FIGURE 4 of the drawings. The securing panel 26 is placed in contact with the interior surface of the panel 30 (FIGURE 3) and maintains the carton 10 in the generally tubular configuration thereof illustrated in FIGURE 3.

The edge portion 35, 41, 53 and 63 loosely embrace the exterior surface (unnumbered) of the container J2 and the curvature thereof corresponds generally to the exterior curvature of the container J2. The edge portions 35, 41, 53 and 63 thereby permit the carton 10 to be secured to a container which has a downwardly and outwardly flared exterior surface.

After the carton 10 has been secured to the container J2 in the manner heretofore described, the flaps or panels 51, 60 are folded radially inwardly along the respective fold lines 46, 57 to a position similar to that illustrated in FIGURE 3 of the drawings. With the closure flaps 22 through 24 open, the jar or container J1 with contents packaged therein and the neck N1 closed by the closure C1 is inserted into a chamber (unnumbered) defined by the carton 10. The closure flaps 22, 23 are then folded into a common plane (FIGURES 1 and 2) after which the closure flap 24 is folded into overlying relationship thereto with the closure tab 25 being directed axially downwardly, in the manner illustrated in FIGURE 4 of the drawings. The natural resiliency of the material from which the carton is constructed tends to urge the flaps 51, 60 to their initial positions in the planes of the respective panels 28, 29, thereby tending to urge the container J1 toward a viewing opening (unnumbered) defined by the severance lines 48, 50, 58, 59 and the fold lines 46, 57. The flaps 51, 60 thereby function as locating means to maintain the container J1 positioned adjacent the viewing window or opening with, for example, indicia on the container readily viewable through the viewing opening.

It is also to be noted that the bottom wall (unnumbered) of the container J1 rests upon the flaps 36, 42, 54 and 65 which function to cushion the container J1 and prevent breakage which might otherwise occur if, for example, the container J1 were constructed from glass or similar frangible material and was subjected to mishandling during storage and/or shipment.

While a preferred form of the invention has been heretofore fully described and illustrated, it is to be understood that the various changes in both the blank 15 and the carton 10 may be made in accordance with this inven-

tion and are considered a part thereof. For example, while the flaps 36, 42, 54 and 65 are preferably folded radially inwardly of the carton 10 as was heretofore described to provide cushioning means between the articles J1 and J2 the tabs may be completely removed along the respective fold lines 38, 44, 56 and 66. In this case the uppermost one of the articles J1 would rest directly upon the closure C2 of the lowermost articles J2.

The panels or flaps 51, 60 can also be removed along the respective fold lines 46, 57, although this construction is less desirable than the illustrated form of the invention.

From the foregoing, it will be seen that novel and advantageous provisions have been made for carrying out the desired end. However, attention is again directed to the fact that additional variations may be made in this invention without departing from the spirit and scope thereof as defined in the appended claims.

I claim:

1. A blank adapted to be folded to form a carton for maintaining a plurality of articles in stacked relationship comprising a relatively planar sheet material member, means for facilitating the folding of said member to a generally tubular configuration to define a chamber adapted to at least partially house a pair of articles in stacked relationship, means for interlockingly engaging the member with a lowermost of the stacked articles, said interlocking means being slot means integrally formed from said sheet material member, and means foldable out of the plane of said sheet material member for forming said slot means and defining means for preventing contact between the stacked articles.

2. The blank as defined in claim 1 wherein said facilitating means is a plurality of fold lines, and said interlocking means is defined by means defining at least a single opening in said member.

3. The blank as defined in claim 1 including means at one edge portion of said blank for closing an upper portion of the chamber, and an edge portion opposite said one edge portion being devoid of closing means.

4. The blank as defined in claim 1 wherein said facilitating means is a plurality of fold lines setting-off rear, first side, front, and second side panels respectively, and said interlocking means is defined by means defining at least a single opening in each of said panels.

5. The blank as defined in claim 1 wherein said member includes a plurality of panels, each of said panels having a free terminal edge portion, and the free terminal edge portion of each panel including means for complementary embracing the exterior of a lowermost of the articles.

6. The blank as defined in claim 5 wherein said complementary means are concavo-convex free edges.

7. A blank adapted to be folded to form a carton for maintaining a plurality of articles in stacked relationship comprising a relatively planar sheet material member, means for facilitating the folding of said member to a generally tubular configuration to define a chamber adapted to at least partially house a pair of articles in stacked relationship, means for interlockingly engaging a member with a lowermost of the stacked articles, said facilitating means being a plurality of fold lines setting-off rear, first side, front and second side panels respectively, said interlocking means being defined by at least a single opening in each of said panels, a closure flap joined to one edge portion of said member, another edge portion of said member opposite said first-mentioned edge portion being devoid of closure means, and means in at least one of said panels between said first-mentioned edge portion and said openings for viewing the uppermost article in the chamber.

8. The blank as defined in claim 7 wherein said viewing means is defined by an opening formed by folding a portion of one of said panels out of the plane of said

one panel, and said portion defines means for cushioning the uppermost article in the chamber.

9. The blank as defined in claim 7 wherein said another edge portion includes means for complementary embracing the exterior of a lowermost of the articles.

10. The blank as defined in claim 7 wherein said another edge portion includes means for complementary embracing the exterior of a lowermost of the articles, said embracing means being a slot formed in said another edge portion between each adjacent pair of said fold lines, each of said single openings being formed by a tab foldable out of the plane of its associated panel, said viewing means being defined by a pair of flaps in an adjacent pair of said panels foldable out of the planes thereof, a fold line joining each flap to its associated panel, and said last-mentioned fold lines being in parallel relationship.

11. A carton for maintaining a plurality of articles in stacked relationship comprising a generally tubular body having axially opposite end portions, said tubular body defining a chamber for housing uppermost and lowermost articles in stacked relationship, means intermediate said opposite end portions for interlockingly engaging the tubular body with one of the articles, and means integrally formed from the material of said body projecting into said chamber and being at all times connected to said body for preventing complete contact between a bottom surface of the uppermost article and a top surface of the lowermost article.

12. The carton as defined in claim 11 wherein said interlocking means is an opening formed in said body.

13. The carton as defined in claim 11 wherein said opposite end portion is of an undulating configuration for matingly embracing an exterior surface of a lowermost one of the articles.

14. The carton as defined in claim 12 including a pair of stacked articles, a lowermost of said articles being a container, said container including a body terminating at an upper end portion in a radially outwardly directed peripheral flange, a portion of said flange being received in said opening, and an uppermost of said articles being housed in said chamber between said lowermost article and closing means above said uppermost article.

15. A carton for maintaining a plurality of articles in stacked relationship comprising a generally tubular body having axially opposite end portions, said tubular body de-

fining a chamber for wholly housing an uppermost article and partially housing a lowermost article, means for closing an uppermost one of said end portions, an opposite one of said end portions being devoid of closing means, 5 means for interlockingly engaging the tubular body with a lowermost of the articles, the lowermost of said articles being a container, said container including a body terminating at an upper end portion in a radially outwardly directed peripheral flange, a portion of said flange being received in said opening, said opening being defined by a flap formed from said tubular body and directed radially inwardly thereof, and the uppermost of said articles being housed in said chamber with a bottom surface of said last-mentioned article at least partially overlying contacting said flap and being cushioned thereby.

16. A carton for maintaining a plurality of articles in stacked relationship comprising a generally tubular body having axially opposite end portions, said tubular body defining a chamber for housing uppermost and lowermost articles in stacked relationship, at least one of said articles having a radially outwardly directed peripheral flange, means for interlockingly engaging the peripheral flange of said one article, said interlocking means being an opening into which said flange is received, said opening being defined by a flap formed from said tubular body and being directed radially inwardly thereof, and the other of said articles being housed in said body with said flap being sandwiched between said uppermost and lowermost articles thereby forming a cushion therebetween.

17. The carton as defined in claim 16 including means for viewing the uppermost article in said chamber, said viewing means being defined by a panel directed into said chamber, and said last-mentioned panel defining means for cushioning the uppermost article in said chamber.
